CALL RECORDING AND CHARGING SYSTEM

Application filed March 11, 1931, Serial No. 521,736, and in Germany June 7, 1930.

It is desirable in telephone systems as well as in telegraph installations with exchanges to determine not only the number of connections set up by subscribers outgoing over the ordinary local exchange, but also the duration of such calls in order to furnish a correct statement of the charges incurred by the calling subscriber. For telephone and telegraph systems with automatic operation it is a known arrangement to divide the network into zones for the determination of the value of set-up connections, in which case each zone has its own tariff and when selected a time switch associated therewith influences the conversation indicator associated with the calling subscriber giving the time and distance corresponding to the zone involved. In this manner the duration of the call as well as the zone is determined to a certain extent.

In this kind of registration of subscriber's connections the disadvantage has often been experienced that the total time during which the junction line has been busy has not been indicated but only the completed or the commenced time sections have been metered. In the first place, it is impossible to carry out a supplementary control over the set-up connections as neither the zone of the set-up connections nor the duration of an individual connection can be obtained from the note made of the conversation indicator, still less then can a special indication of the direction of an individual connection be obtained.

In order to overcome these difficulties electrically driven recording devices are used, according to the invention which automatically, after the setting-up of an operative connection, indicate a designation mark i. e. the name, place number of the like, allocated to the subscriber, by which a subsequent control of the set-up connections is possible. The recording device used for the purpose of denoting the identification marks must, of course, be allocated either to the calling subscriber as he is charged with the account for the calls, or it must also indicate an identification mark for the calling subscriber, when, for the sake of economy, only a limited number of such devices are used as recording

devices. If not only the set-up connection but also its duration is to be metered, a time statement in addition to the noting of the subscriber's identification marks must be taken, which, according to requirements, either indicates only the duration of a connection or else gives an accurate account of the time, date, etc.

The record can be taken in any shape or form suitable for the kind of transmitted subscriber's identification marks or for the time statement. In telegraph systems it is recommended to use a receiving apparatus which is suitable in its operation for the telegraph system so that also the sender used for the transmission of the subscriber's identification marks corresponds in its operation to the devices used for the ordinary work in the system. In this case a particularly advantageous use of the subscriber's identification marks employed for the registration can be carried out in that the identification mark, allocated to the called subscriber, simultaneously with the registration in the exchange is also transmitted to the purpose of supervising the set-up connection as well as for check back to the calling subscriber. The time statement which is taken in order to determine the duration of the connection in the exchange can then also be noted and transmitted to the calling subscriber with the result that he receives a notification of some sort to the extent of his call.

In addition to the transmission of the identification marks or times to the calling subscriber, a transmission to the called subscriber can naturally also be effected in case he desires full particulars of each call in a written statement.

Instead of the receiver, fitted to operate in the system, which can be in the form of a recorder as used in telegraph systems, operating according to the off-and-on principle, which records the received message in clear type, also simple recording devices can be used, which retain the impulses in some form or other, while the transcription of the received signs can be executed later according to requirements. This is of particular advantage when each subscriber is to be sup-

plied with a recording device within an exchange as then a simple tape receiver or the like can, for example, be used in place of expensive recorders. In addition to such a 5 mechanical recording as dots or dashes also other kinds of records can be made. It is possible, for example, to conduct the received impulse to an electromagnet which makes impressions on a passing steel wire corresponding to the nature of the magnetic 10 influences received.

For the reproduction of impulses recorded in this simple manner, a reproducing device can be used which regenerates the recorded 15 impulses and leads them, for example, to a recording receiver which executes the transcription of the impulse groups into readable types. The transcription can be effected at suitable periods, i. e. at the end of the month 20 when the accounts are sent out to the various subscribers.

If an automatic registration of the subscriber's identification marks is to be carried out in telephone systems each individual subscriber must be supplied with a corresponding 25 device which automatically effects the recording of the identification marks, associated with the subscriber, at the switching-through of a connection to a required subscriber. These sending devices can either be installed at the subscriber's stations or else be connected to the subscriber's lines at a suitable position within the exchange. Also in this case it is naturally of vital importance 30 that the notification takes place over the correct junction line of the calling subscriber and this can be guaranteed either by exclusive allocation of the receiving device to the calling subscriber or by recording also of the 35 identification marks associated with the calling subscriber. For a more complete explanation of the features of the invention, embodiments thereof are shown in the drawings which, however, do not limit the possibilities of use in any direction.

Fig. 1 shows the known circuit of a subscriber's connection, set-up over an automatic exchange. Subscriber T1 who is by way of example, a toll line subscriber, can 40 reach the required subscriber T2 by transmitting corresponding impulses by means of his dial over preselector VW1, group selector GW1, and the final selector LW1, with whom he can get into communication on completion 45 of the connection for the purpose of conversation or transmission of telegrams.

A connection set-up in the reverse direction (2) from subscriber T2 to subscriber T1 is effected over other switches VW2, GW2, 50 LW2 as suggested by dotted lines.

An extension of this circuit diagram according to the main features of the invention is shown schematically in Fig. 2. Each subscriber T1 and T2 is now supplied with a sending device S1 and S2, respectively, as

well as a receiving device E1 and E2, respectively, for the purpose of registering the set-up connection. When, for example, the subscriber T1 has reached the subscriber T2, over switches VW1, GW1, and LW1, the 70 sending device S2 responds at the same time or before the completion of the connection, and now transmits an identification signal allocated to subscriber T2, i. e. his name or number in a suitable form backwards over 75 switches LW1, GW1, and VW1 to the receiving device E1 in which the recording of the identification signal is effected. At the same time, the identification signal can be transmitted in a similar manner to the calling subscriber T1 also who thereby receives a check on the set-up connection. After the end of the transmission of the identification signals the set-up connection is prepared for conversation or code signals.

If, in addition to the determining of the subscriber's identification characterized a registration of the extent of the call is to be effected, a time notification can be transmitted from a time recorder Z to the receiving device E1 consisting by way of example, of the exact time of the beginning and end of the conversation. The time recorder can be associated with the receiving device E1 in a simple form and operated in such a manner 80 that it is automatically brought into operation after the complete setting up of a connection or after the transmission of the identification characterized, but it is recommended that a common timing device is 85 used for a plurality of subscribers in the manner shown.

At the setting up a connection from subscriber T2 to T1, which is completed in the direction 2 over switches, VW2, GW2, and 90 LW2, the sending device S1, associated with the called subscriber T1, is brought into operation in a corresponding manner, and transmits an identification signal allocated to subscriber T1 to the receiving device E2 or simultaneously also to the calling subscriber 95 T2.

The connection can be set-up in any manner over a single exchange or a plurality of exchanges.

If a common receiving device for the recording of the subscriber's identification marks is to be used for a plurality of subscribers an arrangement as shown schematically in Fig. 3, by way of example, can be 100 used. When a connection between the subscribers T1 and T2 is set-up the sending device S2 is brought into operation after the completion of the connection as before, but the recording of the identification characteristic is not made by a receiving device directly associated with subscriber T1, but a receiving device E, provided in common for a plurality of subscribers, operates and connects itself at the setting up of a connection 105

by means of a call finder AS1 to the junction line of the calling subscriber. In addition to the sending device S2 the sending device S1, allocated to the calling subscriber T1, also is brought into operation, with the result that a determination of the two subscribers' identification signs is effected. The time records, totaling the extent of calls, can also be transmitted in this case by a common time recorder Z.

Fig. 4a, in conjunction with Fig. 4b, which should be located below Fig. 4a shows the circuit of a telegraph system in which the metering and registration of connections is effected by a telegraph machine EF, (Fig. 4a bottom) which is associated with a large group of subscribers; its connection with the calling subscriber's line is established by a call finder AS which operates automatically when the subscriber puts through a call.

In the middle portion of the drawings the two sending devices KS and KS' intended for the enquiry of the subscriber's identification characteristic are located which are allocated to the subscribers TS and TS', respectively. The impulse combinations which correspond to the subscriber's identification characteristic and which are transmitted over two of the contact wipers of the sending devices KS and KS' are generated in a main sending device SS which is shown in the right-hand bottom part of the drawings (Fig. 4a). The sending device is connected to a time recording mechanism ZS (Fig. 4b) which transmits the time.

In the case of a call from the subscriber's station TS (Fig. 4a) which can be switched through in the shown or any other known manner, a test relay T is energized after the hunting of the preselector VW to a free group selector GW in known manner. The relay T starts the call finder AS of a disengaged registering device over its contact t2 in the circuit: Earth, t2, as1, DAS, r2, u3, LU battery, earth. The interrupter LU advances the driving magnet DAS step-by-step, upon which the circuit, after leaving the first contact, no longer extends over contact t2 but reaches earth direct from the contact bank of the rotary wiper as1.

The test wiper as4, during its hunting to find the contact of the calling subscriber, finds, a test path closed over contact t1 with the result that the test relay R of the call finder AS is energized over: earth, battery, t1, resistance W1, as4, R, earth. The test relay R engages the call finder and thereby the registering device EF by short-circuiting its high resistance winding I by means of contact r1 is set in known manner, while at the same time, the further advancing of the call finder is prevented by the opening of contact r2.

The receiving magnet MR of the registering device EF is now connected to the b-lead

of the busy junction line, over the alternating contact u2 and the rotary wiper as2.

In the meantime the calling subscriber TS, by transmission of selecting impulses by means of the dial contact ns sets up a connection with the required subscriber TS' over the a-lead in known manner, extending over switches VW, GW, and LW. Hereby relays P and C are energized at the operation of the group selector GW to a free final selector LW, the contacts of which in known manner influences the circuit (not shown) for the seizure of the switch connecting up of the junction lines, preparation for the release, etc.

On the hunting of the final selector LW for the line leading to the required subscriber TS' the test relays Q and T' are energized if the subscriber is disengaged. At the same time, the relay H (winding I) is connected up over the test lead of the final selector and causes the identification characteristic mark transmitter KS' allocated to the required subscriber to be operated over: earth, Q, 1c, H', (1), vc1, T', battery, earth.

The identification transmitter KS' operates as soon as contact h'2 is closed: earth, battery DKS', ks4', h2', SK, earth. Contact SK is closed by the cam NK of the main sender SS at regular time intervals in order to fix the correct time for the connecting up of the identification transmitter. On the shaft NW of the main sender which carries the cam NK a further series of cams NS are fitted which serve to guide the impulse contacts associated with the letters and numbers for the identification signs and time record which is achieved by a suitable phase position of the cam NK in relation to the impulse cam NS in this simple manner that the advance of the rotary wipers of the identification sender, transmitting the impulse can only take place in the pauses between the impulse groups corresponding to the individual groups. The driving magnet DKS' of the identification transmitter KS' is intermittently energized in the above-described circuit and thereby advances the rotary wipers KS' and KS4 step-by-step.

In this manner, while the identification transmitter remains on the second contact after the first movement of its rotary magnet DKS', an impulse sequence corresponding to the first letter of the identification signs of the called subscriber is transmitted over the rotary wiper ks3' to the called subscriber TS' at the same time to the registering device EF. The generation of the impulse sequence, corresponding to this letter i. e. "b" is effected by contact hb of the main sender SS which, by the cam NS associated therewith, is closed intermittently according to the impulse sequence over: earth, battery, resistance W2. hb, a'-lead, 1a, b-lead, gb, vb, wiper of call finders as2, u2, MR, earth. The impulse sequence is thus noted by the registering device

EF controlled by the printing magnet MR. At the same time a notification takes place at the calling subscriber's station TS by means of a printing magnet EM of the receiver in case this is required as a check on the setting up of the connection.

After the transmission of the impulse sequence corresponding to the first letter of the identification sign (i. e. "b") further impulse groups are transmitted in a corresponding manner by the connection being set up with corresponding impulse contacts of the main sender by the rotary wiper $ks'3$ of the identification transmitter KS'. The further advance takes place each time in the intervals between the individual impulse groups at the closing of contact SK by means of the cam NK.

In addition to these impulse groups further impulse groups can be transmitted which effect the notification of the exact time or any other time information, and these latter impulse groups can be connected up to the impulse groups which are so combined that they state the name and place of the required subscriber in the recorder of the subscriber TS or in the registering device EF of the exchange. The impulse groups, corresponding to this time statement, are sent out from the time sender ZS (Fig. 4b) the contact wipers SZ, SE, MZ, ME of which complete the connection with the meter impulse contacts $k1$, $k2$, $k3$, and $k4$, etc., of the main sender SS, (Fig. 4a).

The advance of the contact wipers SZ—ME (Fig. 4b) operate the rotary magnets DSZ—DME, associated with them, which are operated in the time periods corresponding to their tariffs by contacts nsz — nme of a time switch device ZU. The arrangement, by way of example, is so made that the contact wiper ME is associated with minute periods and is advanced in periods of one minute for which purpose it is connected in sequence with the impulse contacts ($k1$, etc.) of the main sender corresponding to digits 0 to 9. In a similar manner the advance of the contact wipers MZ associated with ten minute periods, e. g. every ten minutes, while the contact wipers SE and SZ respond to the hour units or ten hour units and are advanced accordingly after longer time periods.

By this arrangement it is achieved that, in connection with the transmission of the identification characteristic of the called subscriber, a transmission of impulses is effected which corresponds exactly to the correct time. Other informative signs, such as stop, common or the like can be transmitted between the records of the time notification and the notification of the time can also be supplemented by the date.

As soon as the time notification is ended, a special impulse combination is transmitted over the last but one contact of the identifica-

tion sender KS' controlling the registering device. This impulse combination which differs from the other signals by its composition is generated by a special impulse contact ku of the main sender and upon its transmission to the receiving magnet MR of the registering device EF, actuates mechanically the closing of a contact UZ which over the test lead of the call finder connects up relay U over: earth, UZ, U, as, W1, $t1$, battery, earth. Relay U remains energized over its own contact $u1$, with the result that the contact UZ can return to normal.

At the same time a fresh circuit for the receiving magnet MR of the registering device EF is prepared by the change-over contact $u2$, which extends over the rotary wiper $as3$ of the call finder AS to the rotary wiper $ks2$ of the identification sender KS allocated to the calling subscriber. This identification transmitter operates, however, only after the cutting-off of the connection in order to transmit simultaneously also the time of the termination of the conversation.

After the transmission of the change-over signal ($u2$) the rotary wiper $ks'3$ of the identification transmitter KS' allocated to the called subscriber is moved to the last contact on which the completion of the connection of the a' -lead to the called subscriber TS' is completed.

The junction line between the subscriber TS and TS' is now engaged for the transmission of the telegram in both directions. During the existing connection the registering device and also the identification transmitter allocated to the two subscribers, are in their normal positions so that an interruption of the transmitted telegram is prevented. At the same time a listening in to the telegram is also prevented by the registering device EF and by the throwing-over of contact $u2$, whereby the secrecy regarding the contents of the telegram is insured.

After the ending of the telegram transmission the test relay T, at the release of the connection, is caused to release by the influence of contacts known per se, which are not shown for the sake of greater lucidity. Thereby a circuit for winding II of relay H is closed over contact $t3$ returning to normal, whereby the identification transmitter KS of the calling subscriber TS is in operation over: earth, battery, H, (II), $t3$, $ks2$, $as3$, $u2$, MR, earth. Contact $h1$ is closed in order to keep the energizing circuit for relays R and U closed as an alternative for the now opening contact $t1$.

The identification transmitter KS starts to operate over contact $h2$ due to its rotary magnet DKS being energized over: earth, battery DKS, $ks4$, $h2$, SK, earth. The guiding contact SK of the main sender SS again, in the manner already described, causes the advance of the wiper of the identification

signal transmitter to be effected in the correct time intervals. Contact h_3 prepares the return of the identification signal transmitter to its original position.

- 5 After the rotary magnet DKS has received an impulse over contact SK and the rotary wipers of the identification signal transmitter KS has moved to the next contact the impulse sequences, generated by the cam contacts of the main sender SS, are transmitted to the receiving magnet MR of the registering device EF: earth, MR, u_2 , as_3 , ks_2 , junction line to main sender, impulse contact (i.e. ka) resistance W2, battery, earth.
- 10 When thus the signal has been transmitted to the called subscriber the transmission of the time notification which is brought about in the above described manner takes place over a second portion of the contact laminations of the rotary wiper ks_2 .

15 As soon as this time notification has been recorded by the recording machine the identification transmitter KS advances to the last contact. In this position the holding circuit 25 for relay H (winding II) is broken which, before, was closed over the hunting laminations of the rotary wiper ks_1 . The relay H releases slowly and closes thereby the restoring circuit for the rotary magnets DKS over 30 its contacts h_2 and h_3 , respectively, with the consequence that this sets the switching mechanism to its original position. Contact h_1 breaks the test circuit for the call finder AS so that relays R and U are deenergized.

35 A circuit for the rotary magnet DAS of the call finder AS is then closed by the return to normal of contacts r_2 and u_3 , which then is set to normal over: earth, as_1 , DAS, r_2 , u_3 , LU, battery, earth.

40 In the meantime the identification transmitter KS' of the called subscriber TS1 has also reached its original position, as at the release of the connection, the relay H1, (winding I) located in the test-lead of the final 45 selector LW has released. The rotary magnet DKS' now receives the advancing impulses generated by the interrupter RU', over contact h'_2 or h'_3 , respectively, which bring the rotary wipers to their normal position.

50 All the switching elements concerned in the establishment of a connection are now set back to their original positions and ready for a new call. On the tape of the recording device the statements can be read in plain letters which relate to the set-up connection and the duration of its extension.

55 Fig. 5 shows an arrangement in which each subscriber is supplied with a simple registering device which, by way of example, records the impulses, characterizing the set-up connection and its duration on a steel wire drawn in front of a magnet. Impulses stored in this manner can later be put into clear text by a recording machine transcribing the

signs which form the basis for the statement of account.

In the drawings the recording device consists of an electromagnet SM with windings I and II in front of the poles of which a steel wire X is moved over the drums Y1 and Y2. The winding I is influenced at the setting-up of a connection by the identification transmitter allocated to the called subscriber, while winding II can be brought into operation by a time recorder ZG, shown in the left bottom portion of the drawings, for the purpose of recording the time notifications indicating the duration of the call. A notification of the identification signal allocated to the calling subscriber is not necessary in this case as each individual recording device is associated with only one individual subscriber. In order to make the case clearer only the identification transmitter KS', allocated to the called subscriber TS', is shown in the drawings, while the one for the calling subscriber TS has been omitted.

The number of time recorders ZG required in a system can be comparatively small as it is sufficient if, at the establishment and release of a connection, a short connecting up of the recording magnet SM to a free time recorder is effected. The selection of a disengaged time recorder is performed, by way of example, by a call finder AS allocated to a group of subscribers.

When, for example the subscriber TS wishes to transmit a telegram to the subscriber TS' he sets-up the connection selectively by means of his dial in manner known per se over the switches VW, GW, and LW. On the setting-up of the connection the test relays T, B, P, C, Q and T' are energized in the individual selecting stages and are schematically shown in the diagram. In addition the relay H' (winding I) is energized in the circuit of the test wiper $1c$ of the final selector LW and starts the identification transmitter KS' of the required subscriber in the already described manner by the throwing over of contact h'_1 . The switching operation is performed in regular time intervals at the energization of the driving magnet DKS' over the cam contact SK of the main sender SS, while over the contact wiper ks'_1 the impulse groups, transmitted by the same to the letter contacts ka , kb , kc , etc., of the main sender are meanwhile sent in the a' -lead in the sequence which corresponds to the identification signals of the subscriber TS'.

These impulse groups now reach the winding I of the recording magnet SM of the registering device over contact wiper $1a$ of the final selector LW, the contact wiper gb of the group selector GW and the wiper vb of the preselector VW and further the receiving magnet SM of the calling subscriber TS. The recording magnet SM thereon records the transmitted impulses of the iden-

ification signals on the steel wire X, passing in front of its poles, which in the meantime, has been set in motion, while the receiving magnet EM of the subscriber TS immediately transcribes the identification signals into clear type, so that the calling subscriber receives a check of the set-up connection.

Relay U (winding I) which is placed in series with the winding of the recording magnet SM is constructed in such a manner that it is not energized by the signal impulses. It operates with a slow-acting armature and the slow action period is so calculated that it cannot respond to the short signal impulses. Only when the contact wiper $ks'1$ of the identification transmitter KS' connects battery to the a -lead on one or a plurality of contacts located in front of the last contact over resistance W4 for a longer period can relay U (winding I) be energized. It then closes a circuit by means of its contact $u2$ for the holding winding II which at the response of the test relay T, has been prepared by the closing of contact $t1$. The alternating contact $u1$ disconnects the winding I of the recording magnet SM and effects, at the same time, the immediate connecting up of the b -lead of the calling subscriber TS.

Instead of the slow-acting relay U any other device can be used which operates in the same manner over the a -lead or b -lead from the identification transmitter KS' of the called subscriber. It is possible, for example, to use a polarized relay which remains in one position during the transmission of the identification impulses and which receives an impulse of opposing current direction at the last but one step of the contact wiper $ks'1$ which it momentarily guides to another position.

After the connecting up of the b -lead of the calling subscriber TS by the throwing-over of contact $u1$ the a -lead of the called subscriber TS' is also connected up as the contact wiper $ks'1$ of the identification transmitter KS' moves to the last contact. On this contact the identification transmitter remains until the release of the connection takes place.

The connection between the two subscribers is now set-up and the transmission of the telegram can commence.

In the meantime the call finder AS of the time recorder ZG has been started over contact $u5$ and a circuit for the rotary magnet DAS of the call finder has been closed over: earth, $h3$, $u5$, $as3$, DAS, $r4$, UAS, battery, earth.

The interrupter UAS now advances the switch over the contact bank of the rotary wiper $as3$ until the test wiper $as1$ reaches the contact laminations of the calling subscriber and the test relay R is energized over: earth, battery, $u4$, H (II), $h2$, $as1$, $zg1$, R, earth.

The test relay R responds and engages, at the

same time, the call finder by short-circuiting its high resistance winding I by means of contact $r1$. The circuit for the continued switching operation is broken by contact $r4$ with the result that the call finder remains in the position which it has reached.

Relay H, the lower resistance winding II of which is connected up in series with a test relay R in the test lead of the call finder in turn also remains unenergized. Only in the moment when it receives an increased current by the closing of the controlling contact SK of the main sender over the already closed contact $r2$ is it caused to operate over: earth, battery, $u4$, H (II), $h2$, $as1$, $r2$, SK, earth. It then throws over its contact $h2$ and remains energized over this in addition to the closed contact $t3$ of the test relay T.

Simultaneously with the connecting up of relay H the rotary magnet DZG of the time recorder ZG is also energized, with the consequence that the test relay R remains energized over the traversing contact bank of the rotary wiper $zg1$ and resistance W1. The rotary magnet DZG is connected up in the following circuit: earth, battery, DZG, $zg3$, $r5$, SK, earth. Now the time recorder ZG also advances step-by-step according to the operation of the identification transmitter by the contact SK controlled by the main sender SS, at which the rotary wiper $zg2$ sets-up the connection with the contact wipers SZ—ME of the time switching device in succession. The contact wipers SZ—ME are set to the contacts, indicating the time in the manner described for Fig. 4b, by the rotary magnets DSZ—DME, controlled by a time switch ZU. These contacts are connected to the impulse contacts $h1$, $h2$, $h3$, etc., of the main sender SS.

At the hunting of the wipers SZ—ME by the contact wiper $zg2$ of the time recorder, successive impulse groups are transmitted, the combination of which indicates the time. When noting down is effected by the recording magnet SM, the winding II of which is connected to the contact wiper $zg2$ over: $u3$, $as2$, and $r3$.

As soon as the time recorder ZG has reached its last contact the rotary magnet DZG is disconnected from the main sender. At the same time the test relay R, however, is deenergized as the contact wiper $zg1$ has reached a free contact and returned contact $r6$ to normal, which causes a renewed energization of the rotary magnet DZG over the interrupter UZG. The time recorder is thus operated until it has reached its original position.

At the release of that test relay R also contact $r4$ was closed so that the call finder AS can also return to normal. A renewed starting of the call finder cannot now take place as relays H and T remain energized and contacts $t2$ and $h3$ open. The time recorder

is thus ready for a fresh call a short time after effecting the connection between the two subscribers.

A renewed connecting up of the time recorder for the connection mentioned can only take place when the test relay T, of the calling subscriber TS is deenergized at the release of the connection. A free time recorder for the notification of the end of the call is then again started over contact t_2 as the rotary magnet DAS of the call finder AS is connected up over contact wiper as_3 in the already described manner. The test circuit for the call finder is then closed over contact t_4 as relay H is energized and contact h_2 thrown over. Thus the contact t_3 is opened but the relay H (II) yet remains energized during the time notification, as it receives the impulse transmitted by the controlling contact SK over the test wiper as_1 of the call finder and over contact r_2 after the response of the test relay R. Relay H is constructed in the form of a very slow-acting relay. Thereby is achieved that relay U (II) remains connected up over contact h_1 during the time notification.

After the transmission of the impulse groups, corresponding to the time of the end of the call, which is effected in the already described manner, the test relay R is again deenergized when the time recorder reaches the last but one contact, with the result that the time recorder returns to its starting position. Hereby relay H also is deenergized with a slow action and causes also the de-energization of relay U at the opening of contact h_1 .

The system now is again prepared for further calls as in the meantime the identification transmitter KS' of the called subscriber also has been brought to its original position at the release of the connection by the release of relay H'.

The steel wire X which is brought to rest after the ending of each time notification now carries the transmitted impulses which later can be transcribed into ordinary type by a special printing machine at a calculation of the charges incurred.

50 What is claimed is:

1. In a call recording and charging system, calling and called subscribers' lines, means for establishing a connection between a calling line and a called line, means automatically operative responsive to the establishment of said connection in case the called line is idle for transmitting back over the established connection an identification signal assigned to the called subscriber's line, and a recorder associated with said calling line operated responsive to said transmission for recording said called line identification signal.

2. In a call recording and charging system, calling and called subscribers' lines,

means for establishing a connection between a calling line and a called line, means automatically operative responsive to the establishment of said connection in case the called line is idle for transmitting back over the established connection an identification signal assigned to the called subscriber's line, a recorder associated with said calling line operated responsive to said transmission for recording said called line identification signal, means for transmitting an identification signal assigned to the calling line to said recorder, and means responsive thereto for operating said recorder to record the calling line identification signal.

3. In a call recording and charging system, calling and called subscribers' lines, means for establishing a connection between a calling line and a called line, means operative in case the called line is idle for transmitting back over the established connection an identification signal assigned to the called line and the time of day, a recorder temporarily associated with the calling line responsive to the establishment of said connection and operated responsive to said transmission for recording said called line identification signal and time of day, means for releasing said connection, and means responsive thereto for transmitting an identification signal assigned to the calling line and the time of day to said recorder for operating said recorder to record the calling line identification signal and the time of day whereby the duration of the call is likewise recorded.

4. In a call recording and charging system, calling and called subscribers' lines, a recorder individual to each of said calling lines, a recorder common to said calling lines, means for establishing a connection between a calling line and a called line, means for associating said common recorder with said calling line, means automatically operative responsive to the establishment of said connection in case said called line is idle for transmitting back over said established connection an identification signal assigned to the called subscriber's line, and means responsive to said transmission for operating both the individual and the common recorders to record the called line identification signal.

5. In a call recording and charging system, calling and called subscribers' lines, a recorder individual to each of said calling lines, a recorder common to said calling lines, means for establishing a connection between a calling line and a called line, means for associating said common recorder with said calling line, means automatically operative responsive to the establishment of said connection in case said called line is idle for transmitting back over said established connection an identification signal assigned to the called subscriber's line, and time signals,

and means responsive to said transmission for operating both the individual and the common recorders to record the called line identification signal and said time signals.

- 5 6. In a call recording and charging system, calling and called subscribers' lines, an impulse sender common to said lines, a switch individual to each line having their bank contacts wired to said impulse sender in accordance with their assigned numbers, a recorder, means for establishing a connection between a calling line and a called line, means responsive to the establishment of said connection for connecting the switch individual 70 to the called line to said sender, means controlled by said sender for operating said individual switch and for transmitting a signal indicative of the called line over the contacts of the individual switch and said connection, 75 and means responsive to said transmission for operating said recorder to record the called subscriber's signal.

- 20 7. In a call recording and charging system, calling and called subscribers' lines, an impulse sender common to said lines, a time switch common to said lines, a switch individual to each of said lines having their bank contacts wired to said sender in accordance with their assigned numbers and to said time switch, a recorder, means for establishing a connection between a calling and a called line, means controlled by said sender responsive to the establishment of said connection for operating the switch individual to the 90 called line and for transmitting a signal indicative of the called line and the time of day over the contacts and said connection, and means responsive to said transmission for operating said recorder to record the called subscriber's signal and the time of day.

- 40 8. In a call recording and charging system, calling and called subscribers' lines, an impulse sender common to said lines, a switch individual to each of said lines having their bank contacts wired to said sender in accordance with their assigned numbers, a recorder, means for establishing a connection between a calling and a called line, means controlled by said sender responsive to the establishment of said connection for operating the switch individual to the called line and for transmitting a signal indicative of the called line over the contacts of said individual switch and said connection, means for releasing said connection, means controlled by said sender responsive to said disconnection for operating the switch individual to the calling line and for transmitting a signal indicative of the calling line over the contacts of the switch individual to the calling line, and means responsive to both transmissions for operating said recorder to record the called and calling subscribers' signals.

- 45 9. In a call recording and charging system, calling and called subscribers' lines, an

impulse sender common to said lines, a time switch common to said lines, a switch individual to each of said lines connected to said sender and time switch, a recorder, means for establishing a connection between a calling and a called line, means controlled by said sender and time switch responsive to the establishment of said connection for operating the switch individual to the called line and for transmitting a signal indicative of said called line and the time of day over said connection, means for releasing said connection, means controlled by said sender and time switch responsive to said disconnection for operating the switch individual to the calling line and for transmitting a signal indicative of said calling line and the time of day, and means responsive to both transmissions for operating said recorder to record the called and calling subscribers' identification signals 85 and the time of day the connection was established and released.

- 10 10. In a call recording and charging system, calling and called subscribers' lines, means for establishing a connection between a calling line and a called line, means responsive to the establishment of said connection for transmitting an identification signal assigned to the called subscriber's line, and a recorder associated with said calling line operated responsive to said transmission for recording said called line identification signal.

- 11 11. In a call recording and charging system, calling and called subscribers' lines, means for establishing a connection between a calling line and a called line, means responsive to the establishment of said connection for transmitting an identification signal assigned to the called subscriber's line, a recorder operated responsive to said transmission for recording said called line identification signal, means for transmitting an identification signal assigned to the calling line to said recorder, and means responsive thereto for operating said recorder to record the calling line identification signal.

- 120 12. In a call recording and charging system, calling and called subscribers' lines, means for establishing a connection between a calling line and a called line, means for transmitting an identification signal assigned to the called line and the time of day, a recorder operated responsive to said transmission for recording said calling line identification signal and time of day, means for releasing said connection, and means responsive thereto for transmitting an identification signal assigned to the calling line and the time of day to said recorder for operating said recorder to record the calling line identification signal and the time of day whereby the duration of the call is likewise recorded.

- 125 13. In a call recording and charging system, calling and called subscribers' lines, a

recorder individual to each of said calling lines, a recorder common to said calling lines, means for establishing a connection between a calling line and a called line, means for associating said common recorder with said calling line, means automatically operative responsive to the establishment of said connection for transmitting an identification signal assigned to the called subscriber's line, and means responsive to said transmission for operating both the individual and the common recorders to record the called line identification signal.

In witness whereof, I hereunto subscribe my name this 27th day of January, A. D. 1931.

PAUL STORCH.

In witness whereof, I hereunto subscribe my name this 27th day of January, A. D. 1931.

EHRHARD ROSSBERG.
